(57) **CLAIM**

The ornamental design for a shower strainer, as shown and described.

DESCRIPTION

FIG. 1 is a perspective view of the shower strainer embodying all embodiments of my new design;

FIG. 2 is a top view of the shower strainer embodying all embodiments of the design;

FIG. 3 is a side view of the shower strainer embodying all embodiments of the design;

FIG. 4 is an exploded view of the shower strainer of a first embodiment of the design;

FIG. 5 is a second exploded view of the shower strainer of a first embodiment of the design;

FIG. 6 is a bottom view of the shower strainer cap of a first embodiment of the design;

FIG. 7 is a top view of the shower strainer adaptor of a first embodiment of the design;

FIG. 8 is an exploded view of the shower strainer adaptor of an embodiment variant of the design;

FIG. 9 is a bottom view of the shower strainer cap of a second embodiment of the design;

FIG. 10 is a top view of the shower strainer adaptor of a second embodiment of the design;

FIG. 11 is an exploded view of the shower strainer of a third embodiment;

FIG. 12 is a bottom view of the shower strainer cap of a third embodiment of the design;

FIG. 13 is a top view of the shower strainer adaptor of a third embodiment of the design;

FIG. 14 is an exploded view of the shower strainer adaptor of a fourth embodiment of the design;

FIG. 15 is a bottom view of the shower strainer cap of a fourth embodiment of the design;

FIG. 16 is a top view of the shower strainer adaptor of a fourth embodiment of the design;

FIG. 17 is an exploded view of the shower strainer of a fifth embodiment of the design;

FIG. 18 is a bottom view of the shower strainer cap of a fifth embodiment of the design;

FIG. 19 is a top view of the shower strainer adaptor of a fifth embodiment of the design;

FIG. 20 is an exploded view of the shower strainer adaptor of a sixth embodiment of the design;

FIG. 21 is a bottom view of the shower strainer cap of a sixth embodiment of the design; and,

FIG. 22 is a top view of the shower strainer adaptor of a sixth embodiment of the design.

Any broken lines shown in FIGS. 1-22 are included for the purpose of illustrating the environment of the articles in use and those portions of the article form no part of the claimed design.
